TOY GUN HAVING A ROTATABLE MAGAZINE

Just Wolf, Paris, France

Application February 28, 1946, Serial No. 650,864
In France August 7, 1945

3 Claims. (Cl. 124—27)

1

This invention relates to a toy in the form of a rifle, pistol, revolver, machine gun and the like and it has for its purpose to provide a toy made to imitate a repeating fire arm, which is of a simple and inexpensive construction and is adapted to shoot a plurality of projectiles in rapid succession in repetition firing.

In the accompanying drawings given by way of example:

Fig. 1 is a fragmentary plan view of one embodiment of the toy according to the invention.

Fig. 2 is an elevational view partly in section, corresponding to Fig. 1.

Fig. 2a is a fragmentary enlarged vertical sectional view of the detent release mechanism.

Fig. 3 is an inverted plan view of the magazine.

Fig. 4 is an elevational view, partly in section, of a second embodiment.

Fig. 5 is a front view corresponding to Fig. 4.

Fig. 6 shows a longitudinal section of the magazine.

Referring to Figs. 1 to 3, 1 denotes a gun barrel carried by the stock or butt 2 of the toy, said butt being provided at the rear end of the barrel with a horizontal elongated opening 3 through which extends the magazine 4 which is in the shape of a flat circular segment rotatably mounted on the butt by a vertical pin 5 and urged in the direction of the arrow f by the action of a coil spring 6 carried by the pin 5. The magazine 4 is provided with cylindrical chambers 7 extending radially and opening outwardly at the periphery of the magazine, each of them containing a coil spring 8. Upon the lower face of the magazine, in vertical alignment with each chamber 7, is pivoted on a horizontal axis 10 a detent 9 provided at its front end with a catch or nose 11 adapted to extend upwardly into the corresponding chamber 7 of the magazine through a hole 12 provided therein. The nose 11 is urged into the corresponding chamber 7 by a coil spring 13 housed in a recess provided in the magazine and acting on the rear part of the detent.

In a vertical opening provided in the butt 2, is mounted a trigger 14 rotatably supported on an axis 15. A horizontal rod 17 is pivoted at 18 on the trigger and arranged in a slot provided in the body 2 in vertical alignment with the axis of the barrel. When the trigger is depressed, in opposition to the action of a spring 16, a pushing member 19 actuated by the front end of rod 17 will act to raise the rear end of the detent 9 belonging to the chamber 7 which is then in alignment with the barrel.

2

The projectiles are constituted by cylindrical bullets 20 made for instance of wood, each of which is provided in its rear part with an annular notch 21 arranged in such manner that, when the bullet is introduced into one of the chambers 7 by compressing the corresponding spring 8, the nose 11 on the detent will engage the rear wall of the notch 21. The bullet will thus be held in the chamber, in opposition to the action of spring 8 and the front end of the bullet will slightly project outwardly from the periphery of the magazine.

When the arm is loaded, the outwardly projecting end of the bullet which is in alignment with the bore of the barrel is pressed laterally by the action of the spring 6 of the magazine against a side extension or lug 22 provided at the rear end of the barrel.

The operation of the above device is obvious; when the trigger 14 is depressed, the detent 9 of the first chamber 7 is caused to swing vertically, thereby allowing the nose 11 to release the bullet 20 which is projected through the barrel by the corresponding spring 8. Under the action of spring 6, the magazine 4 is then caused to rotate in the direction of arrow f until the bullet 20 in the next chamber 7 comes into engagement with the arresting lug 22 on the barrel and reaches the firing position, and so on.

In order to reload, it is merely necessary to rotate the magazine 4 in the opposite direction to the arrow f to a position slightly beyond the initial position shown in Fig. 1 and to place bullets 20 into the chambers 7.

In the modification shown in Figs. 4 to 6, which is of the revolver type, the parts corresponding to those above described are respectively designated by the same numbers plus 100.

The magazine 104 is in the shape of a revolving cylinder rotatably supported on the butt 102 by a horizontal axis 130 carrying the magazine spring 106. The detents 109 are held in the armed position by an elastic ring 131 of rubber or the like engaging into a notch provided in the outer face of each detent.

The cylinder 104 under the action of spring 106 revolves in the direction of arrow f^1 . It is provided with a radial finger or projection 132 adapted to come into engagement with the bottom wall of a notch 133 formed in the upper part of the butt 102 when the last chamber 107 of the magazine comes finally into alignment with the gun barrel 1. For reloading, the cylinder 104 is rotated in the opposite direction to the arrow f^1 back to its original position.

The invention is of course not limited to the

forms of embodiment shown and described which have been given only by way of example.

Having now described my invention what I claim as new and desire to secure by Letters Patent is:

1. A toy gun comprising in combination a gun butt, a gun barrel on said butt, a spring controlled rotatable magazine pivoted on said butt and having load chambers, propelling springs in said chambers, spring controlled detent members carried by the magazine and adapted to retain a bullet in each of the chambers in such a position that the outer end of the bullet slightly projects outwardly from the corresponding chamber, a trigger mechanism mounted in the gun and having a pushing member acting on the said detent members in succession, and an arresting lug on the rear end of the barrel with which the outer projecting ends of the bullets are adapted to engage in succession.

2. A toy gun as claimed in claim 1, in which the magazine is in the form of a flat circular

segment having load chambers provided therein in radial positions.

3. A toy gun as claimed in claim 1 wherein the magazine is in the form of a revolving cylinder having parallel load chambers provided therein in axial position.

JUST WOLF.
